George L. "Thom" "

UNITED STATES PATENT OFFICE.

GEORGE L. THOM, OF BROOKLYN, NEW YORK, ASSIGNOR TO GEORGE MADISON CO, OF NEW YORK, N. Y., A CORPORATION OF NEW YORK.

DISPLAY-STAND.

1,174,202.

Specification of Letters Patent.

Patented Mar. 7, 1916.

Application filed November 11, 1914. Serial No. 871,496.

To all whom it may concern:

Be it known that I, GEORGE L. THOM, a citizen of the United States, residing at Brooklyn, in the county of Kings and State 5 of New York, have invented certain new and useful Improvements in Display-Stands; and I do hereby declare the following to be a full, clear, and exact description of the invention, such as will enable others skilled 10 in the art to which it appertains to make and use the same.

This invention relates to display stands and more particularly to that type of stand 15 for supporting an electric lamp upon which a revolving display, as shown in Patent No. 807,841, to P. H. Korst, is mounted.

An object of this invention is to provide a support for an incandescent lamp socket so that said socket may be maintained in up- 20 right position.

A further object of this invention is a provision of a socket support formed of two pieces of material such as cardboard or the like.

25 A further object of this invention is to provide a support for a revolving advertising display in which the support may equally serve as an advertising medium.

Further objects will be apparent from the 30 following specification, appended claims and drawings in which—

Figure 1 shows a perspective view of a suspended support having a revolving display carried thereby, Fig. 2 is a perspective view of the support showing the parts about 35 to be assembled, Fig. 3 is a perspective view of the support combined with a cutout advertising display, Fig. 4 shows the support in the form of a bracket and Figs. 5 and 6 40 show plan views of the blanks comprising a support of a pedestal formation.

As it is possible to place a revolving display upon an incandescent electric lamp in such a manner as to permit said revolving 45 display to operate by the heat generated by said lamp, it is necessary to provide a simple support whereby the socket in which an electric lamp is placed, may be maintained in upright position. This application 50 presents a simple device which serves this purpose and it is understood that the material of which the several forms to be described are made, is not restricted to any particular line of material as it is possible

to use cardboard, fiber-board or metal with 55 equal satisfaction.

Referring to the drawings in which the several forms are shown, 10 indicates an electric fixture having the ordinary lamp socket 11 secured thereto and in this socket 60 is placed the usual extension plug 12 to which the terminals of the flexible cord 13 are connected and the opposite terminals of said flexible cord are properly secured in an ordinary socket 14 which supports an in- 65 candescent light upon which a revolving display 15 is rotatably mounted.

As this device is intended to coöperate with the Korst patent in producing a complete product, this device will be described 70 as the support for the electric fixtures in use with the Korst patent and this support comprises a blank 16 which may have a lug 17 formed thereon which is threaded through the strands of the flexible cord as shown in 75 Fig. 1. It may also be desirous of having a similar lug 18 struck from the blank to support the wire between the lug 17 and the socket supporting portion.

The blank has a bottom portion 19 which, 80 as shown, has tongues 20 rising therefrom in spaced relation to form a recess 21 having the reduced portions 22 and 23 to receive an ordinary lamp socket. The tongues 20 terminate in the lugs 24 for the purposes here- 85 inafter described. In placing the socket in the holder, the enlarged portion thereof enters the recess 21, the reduced end in which the bushing is placed through which the wires enter the socket, enters the reduced 90 portion 22 of the recess and the slot 23 receives a portion of the coacting member 25.

Coöoperating with the base just described, is a blank 25 which is slotted as at 26 to allow 95 said blank being placed upon the support 19 and to form tongues which straddle the opposite sides of the base 19 to maintain the blank 25 in vertical position. This blank is recessed as at 27 to correspond with the recess 22 of the base 19 and in forming 100 a bendable portion 28, a tongue 29 is struck from the blank 25 substantially as shown, to allow the portions 28 and 29 being bent from the common plane of the portion 25. 105 This bent portion is recessed as at 30 and has slots 31 extending into the ends 28 and 29 as shown, and when the parts 28 and 29

are bent, the recess 32 is formed and corresponds with the recess 21.

In making the blank 25, the parts 28 and 29 are in the same plane as the major portion thereof, but the blank 29 is outlined as shown in Fig. 6 and said blank is scored to allow the parts 28 and 29 to be bent to the form shown in Fig. 2. The electric socket is then inserted in the blank by passing the 10 threaded end in which the electric bulb is inserted, through the opening 30 and the body portion of the socket in the recess 32. The blank 25 with a socket mounted therein, is then passed through the recesses 21, 22, 15 and 23 to cause the socket to engage in the recess 21 and at the same time to cause the lugs 24 to pass up through the slots 31 when the device is properly assembled.

In Figs. 3, there is shown a cutout 34 to 20 which an easel 35 may be attached and the upper end of this cutout is recessed in a manner similar to the base 19, in which the blank 25 may be assembled thereto.

Fig. 4 is quite the same in having a 25 bracket 36 to which the tongues 37 and 38 are formed and in having said tongues engage screw eyes 39 which may be placed in the wall or any frame upon which the bracket is desired to be mounted. This 30 bracket is provided with the recesses similar to those in the base 19.

Figs. 5 and 6 show the two elements of the support which when made up, present a pedestal and in each of the component 35 blanks, similar elements exist and as shown, 40 indicates one base having legs 41 formed thereon and 42 is a complemental member having legs 43 formed thereon as well as showing by dotted lines at 44, an indication 40 for a scoring to enable the members 28 and 29 being swung with respect to the major portion in that blank.

It is apparent from the foregoing that 45 when the two members are assembled, they cross each other and serve to reinforce each other along the lines of intersection. It is also apparent that modifications may be

made without departing from the spirit of the invention.

Having thus described this invention I 50 claim:—

1. In a support of the class described, interlocking complemental members, having recesses of the configuration of a lamp socket formed therein, one of said members 55 having an enlarged advertisement bearing space, and one of said members having a bendable retaining ring formed thereon, for engagement with the other member.

2. In a support of the class described, interlocking complemental members, each of said members being cut to form a recess having the configuration of the exterior lines of a lamp socket, each of said members having a slot formed therein to receive a portion of 65 the other member therein, and a retaining ring formed on one of said members, to retain a socket in said recesses, and to engage the other member, to hold said members in proper relation. 70

3. In a support of the class described, interlocking complemental members, each of said members being slotted to receive portions of the other member in said slot, a retaining ring formed on one of said members, 75 and bendable with respect thereto, and lugs formed on the other of said members to receive said retaining ring.

4. In a support of the class described, interlocking complemental members, one of 80 said members having an enlarged display space thereon, a lamp receiving recess formed therein, and the other of said members having a recess formed therein to conform with the lamp receiving recess formed 85 in the other of said members, and a bendable retaining portion for engagement with said first mentioned member.

In testimony whereof I affix my signature in presence of two witnesses.

GEORGE L. THOM.
